SWIM BOARD

Roger A. Del Mar, Los Angeles, Calif., assignor to Aeroplastics Corporation, Venice, Calif., a corporation of California

Filed Jan. 16, 1961, Ser. No. 63,569

Term of patent 7 years

(Cl. D71—1)

I claim:

The ornamental design for a swim board as shown.
